FIG. 1.

FIG. 2.

FIG. 3.

FIG. 4.

FIG. 5.

FIG. 1 is a perspective view of a floodlight, showing our new design;

FIG. 2 is a top plan view of the floodlight illustrated in FIG. 1;

FIG. 3 is a side elevational view of the floodlight illustrated in FIG. 1;

FIG. 4 is a front elevational view of the floodlight illustrated in FIG. 1; and

FIG. 5 is a rear elevational view of the floodlight illustrated in FIG. 1.

The dominant features of our design for a floodlight reside in the portions shown in the full lines which portions are further characterized by the non-planar side panels of the housing as illustrated.

We claim:

The ornamental design for a floodlight, substantially as shown and described.
